CLAIM

The ornamental design for a user interface, as shown and described.

DESCRIPTION

FIG. 1 is a perspective view of a user interface showing our new design;

FIG. 2 is a top plan view thereof;

FIG. 3 is a bottom plan view thereof;

FIG. 4 is a side elevational view thereof;

FIG. 5 is an opposite side elevational view thereof;

FIG. 6 is a rear elevational view thereof; and,

FIG. 7 is a front elevational view thereof.

The broken-line disclosure in the views is for illustrative purposes only and forms no part of the claimed design.
